[57] CLAIM

The ornamental design for an electronics enclosure, as shown and described.

DESCRIPTION

FIG. 1 is a perspective view showing the front, side and top of a first embodiment of the new electronics enclosure.

FIG. 2 is a front view of a first embodiment of the new electronics enclosure.

FIG. 3 is a rear view of a first embodiment of the new electronics enclosure.

FIG. 4 is a left side view of a first embodiment of the new electronics enclosure.

FIG. 5 is a right side view of a first embodiment of the new electronics enclosure.

FIG. 6 is a top view of a first embodiment of the new electronics enclosure.

FIG. 7 is a bottom view of a first embodiment of the electronics enclosure; and,

FIG. 8 is a front view showing a second embodiment of the electronics enclosure, showing colors that are associated with portions of the enclosure design.

The electronics enclosure may be used as a housing for a video teleconferencing system. The front of the electronics enclosure has a concave curvilinear portion which partially surrounds a convex curvilinear portion. In the alternative second embodiment, the concave curvilinear portion is grey, as indicated in FIG. 8 by the series of dotted parallel horizontal lines (i.e., -----), and the entire surface of the convex curvilinear portion is blue, as indicated in FIG. 8 by the series of solid parallel horizontal lines (i.e., ____).
